UNITED STATES PATENT OFFICE.

JOSEPH L. SHEARD AND EDGAR E. DUTTON, OF FALLSDALE, PENNSYLVANIA.

HYDROCARBON BLOW-TORCH.

1,092,756.

Specification of Letters Patent.

Patented Apr. 7, 1914.

Application filed November 18, 1913. Serial No. 801,670.

To all whom it may concern:

Be it known that we, JOSEPH L. SHEARD and EDGAR E. DUTTON, citizens of the United States, residing at Fallsdale, in the county 5 of Wayne and State of Pennsylvania, have invented a new and useful Hydrocarbon Blow-Torch, of which the following is a specification.

The present invention appertains to blow 10 torches, and aims to provide a novel and improved device of that character.

It is the object of the present invention to provide a hydrocarbon blow torch embodying a fuel tank or font carrying a 15 burner, and a supporting base for the tank, for permitting the tank to be adjusted at various angular positions with respect to the base, whereby the device may be employed upon inclined or sloping surfaces, as 20 well as level ones, and whereby the burner may be tilted for purpose of brazing, or the like.

Another object of the present invention is to provide a blow torch of the nature indicated, the burner and tank of which embody means for supporting a plumber's 25 solder tool or iron, in order that the bit may be readily heated.

A further object of the present invention 30 is the provision of a unique burner, embodying novel means for controlling the discharge of vapors.

The present invention also comprehends the provision of a hydrocarbon blow torch 35 embodying a novel assemblage of parts, to best adapt the device for the purposes intended, and whereby the structure will be comparatively simple, compact and inexpensive, as well as convenient, practical and 40 efficient in its use.

With the foregoing and other objects in view, which will be apparent as the description proceeds, the invention resides in the combination and arrangement of parts and 45 in the details of construction hereinafter described and claimed, it being understood that changes in the precise embodiment of the invention herein disclosed can be made within the scope of what is claimed without 50 departing from the spirit of the invention.

The invention has been illustrated in its preferred embodiment in the accompanying drawing, wherein:—

Figure 1 is a side elevation of the blow 55 torch. Fig. 2 is a rear or back view thereof.

Fig. 3 is a horizontal section taken on the line 3—3 of Fig. 1. Fig. 4 is an enlarged sectional detail of the burner. Fig. 5 is plan view in detail of the vapor controlling means.

In carrying out the present invention, the tank or font 1, for the kerosene or other hydrocarbonous fuel, is carried by a base 2, which is preferably in the form of a ring or annulus, and which has a pair of up- 60 standing resilient standards or arms 3, the upper terminal portions of which receive the trunnions 4 attached to diametrically opposite sides of the tank 1. The trunnions 4 are journaled through the standards 3 65 and permit the tank or can 1 to be tilted at various angles with respect to the base, a clamping nut or hand wheel 5 being preferably threaded upon one of the trunnions 4, to clamp the fuel tank or can at any 70 position to which it is swung.

The fuel tank 1 is provided with a handle 6 upon its upper end or top, which is preferably disposed at right angles to the common axis of the trunnions 4, and a pump 7 80 is carried by the back side of the tank 1, for injecting air into the tank to bring the fuel under pressure so as to feed the fuel to the burner designated generally at 8.

The burner 8, which is disposed at the 85 front side of the tank 1, comprises an upright spiral generating or retort coil 9, the upper terminal of which is connected to the lower portion of the tank 1, by means of a supply pipe 10. The coil 9 is surrounded 90 by a casing or flue 11, having the pivoted damper 12 at its lower end, and having a collar 13 slipped over its upper end and provided with brackets 14 supporting a ring or annulus 15. The bit of a plumber's 95 solder iron, or any other object to be heated, may be placed upon the ring or annulus 15 over the coil 9, the flames passing upwardly through the coil 9, as will hereinafter appear.

Upon that end of the handle 6 remote 100 from the burner is secured a cross rod 16, preferably having its ends upturned, whereby the said rod provides a seat for the shank of a plumber's solder iron, or the like, which 105 is of advantage in connection with the ring or annular seat 15.

To the lower end or extremity of the coil 9, is attached one arm or branch of an elbow 17, having a strainer 17^a, the other or free 110

arm of the elbow projecting horizontally to intersect the axis of the coil 9. The free arm of the elbow 17 is provided with an upper outlet aperture 18 lying in the axis of the coil 9, or being co-axial with the coil. 5 From the retort or generating coil 9, the vapor is adapted to be discharged through the aperture 18 axially through the coil, to heat the coil for the generation of the fuel, 10 and to heat an object placed upon the annular seat 15.

The discharge of vapor through the aperture 18 is controlled as follows: The free arm of the elbow 17 is provided with a 15 radial horizontally projecting arm 19 having a longitudinal slot or opening, and a bracket 20 comprising a doubled bar, or the like, has one end clamped upon the arm 19 by means of a clamping screw or the like, 20 21, engaged through the slotted arm 19 and taking into the respective extremity of the bracket 20. The upper free portion or leaf 22 of the bracket 20 is slightly raised, and has pivoted thereto, a controlling lever 23, 25 the inner end of which projects over the aperture 18, and carries a depending needle valve 24 projecting toward and co-operating with the aperture 18. An adjusting screw 25 is threaded through the outer end of the 30 lever 23, to seat upon the free end of the bracket 20. A brace 26 is preferably engaged at one end to the screw 21, and at the other end to the tank or can 1, to assist in supporting the burner.

35 When the burner is in operation, the flames will impinge against the coil 9 to generate the fuel, and will pass upwardly to heat an article placed upon the burner, it being observed that the needle valve 24 40 in standing over the aperture 18, will somewhat serve to spread the flames against the convolutions of the retort coil, the casing or flue 11 confining the flames, and the damper 12 controlling the current of air 45 passing upwardly through the flue 11 to assist in combustion. By adjusting the screw 25, the lever 23, may be adjusted to regulate the position of the needle valve 24, whereby the flow of vapor may be regulated 50 to a nicety, it being observed that the outer ends of the bracket 20 and lever 23 pass through an opening provided in the casing or flue 11. By properly manipulating the lever 23, any matter accumulating within 55 the aperture 18, may be dislodged, to prevent the aperture from becoming clogged up.

Attention is directed to the fact that the base 2 may be set upon an inclined surface, such as a roof of any pitch, it being possible 60 to adjust the tank or font 1 to vertical position, in order that the object to be heated may be properly supported upon the burner and tank.

As illustrated in Fig. 1, a plumber's soldering tool or iron T may be conveniently

placed upon the seats 15 and 16, the annular seat 15 accommodating the bit, while the seat 16 is adapted to receive the shank or handle. It is also possible to tilt the tank 1, or to swing it to horizontal position, in order that 70 the burner may be employed for brazing, and kindred purposes.

From the foregoing description, taken in connection with the drawing, the other advantages and capabilities of the present device will be obvious to those versed in the art, and need not be itemized at length, it being observed that the objects aimed at have been carried out satisfactorily. 75

Having thus described the invention, what 80 is claimed as new is:—

1. In a device of the character described, a base, a fuel tank pivotally carried thereby, an upright burner disposed at one side of and connected to the tank, and seats carried 85 by the upper ends of the burner and tank for supporting an object.

2. In a device of the character described, a base, having a pair of standards, a fuel tank trunnioned between the standards, an 90 upright burner disposed at one side of and attached to the tank, and co-operating seats carried by the upper ends of the burner and the tank for supporting an object.

3. In a device of the character described, 95 a base, a tank pivotally carried thereby, an upright burner disposed at one side of and connected to the tank, and including an upper annular seat, a handle for the upper end of the tank, and a seat carried by the handle 100 and co-operating with the aforesaid seat to support an object thereon.

4. In a device of the character described, a fuel tank, an upright retort coil having its upper terminal connected thereto, the 105 lower end of the coil having an outlet aperture directed upwardly therethrough, a vapor controlling needle valve mounted adjustably over the outlet aperture, a flue surrounding the retort coil, and a damper carried by the lower end of the flue. 110

5. In a device of the character described, a fuel tank, an upright retort coil disposed at one side thereof, and having its upper terminal connected thereto, the lower end of the coil having an outlet aperture directed upwardly therethrough, a vapor controlling needle valve mounted adjustably over the outlet aperture, a flue surrounding the retort coil, an annular seat carried by the upper end of the flue, and a seat member carried by the upper end of the tank and co-operating with the aforesaid seat to support an object thereon. 115

6. In a device of the character described, 125 a fuel tank, a retort coil connected thereto, and having an outlet aperture at its free end directed through the coil, a bracket carried by the free end of the coil, a lever carried by the bracket and having a needle valve at one 130

end between the outlet aperture and coil and coöperating with the outlet aperture to control the passage therethrough and to serve as a spreader, and an adjusting screw carried by the other end of the lever and engaging the bracket.

5 In testimony that we claim the foregoing

as our own, we have hereto affixed our signatures in the presence of two witnesses.

JOSEPH L. SHEARD.
EDGAR E. DUTTON.
